UNITED STATES PATENT OFFICE.

JOHN T. RIDDELL, OF EVANSTON, ILLINOIS.

ART OF FORMING INFLATABLE-BALL COVERS.

Original application filed April 10, 1926, Serial No. 101,217. Divided and this application filed December 29, 1926. Serial No. 157,665.

My invention relates to improvements in methods of making inflatable ball covers, and has for its object the production of balls of uniform shape.

5 Other objects will appear hereinafter.

The invention consists in the novel steps and combinations thereof as hereinafter described and claimed.

The invention will be more readily understood by reference to the accompanying drawings forming a part of this specification, and in which,

10 Fig. 1 is a longitudinal section of apparatus especially well adapted for the carrying out of the invention;

Fig. 2 a section taken substantially on line 2-2 of Fig. 1;

Fig. 3 a section taken substantially on line 3-3 of Fig. 1, the form being illustrated as 20 collapsed; and

Fig. 4 a side elevation of a ball cover completed and ready for reversing.

The preferred form of apparatus for carrying out the invention consists of the collapsible form of an exterior or peripheral shape conforming to the desired interior of the completed ball. The form illustrated consists of a central openwork frame 5 having peripheral portions 6 constituting portions of the periphery of the form and having such desired shape. Retractable end members 7 are slidably mounted in the body or frame thus provided, said end members carrying guide ribs 8 operating in guide grooves 9 in the frame whereby said end members will be guided in their movements. Threaded shafts 10 are mounted as shown in the central frame work 5 of the form and engage suitable thread sockets in the end members 7 whereby, by a rotation of said shafts in opposite directions, the end members 7 will be simultaneously retracted or protruded. The shafts 10 carry bevel gears 11 meshing with bevel gear 12 on a transverse shaft 13. The transverse shaft 13 is also suitably mounted in the central framework of the form and is provided with oppositely threaded portions 14 and 15. Opposite side members 16 are provided in said form as shown and constitute a large portion of the periphery of the sides of the form. These side members 16 are also provided with guide ribs 17 engaging guide grooves 18 in the frame of the form for guiding the movements of said side members. Each of the side members 16

is provided with threaded engagement as shown with the threaded portions of the shaft 13, and shaft 13 is provided with a squared end 19 by means of which the same may be rotated as desired. The squared end 19 is provided with a transverse opening 20 for the reception of a rod or wire for suspending or mounting the form and also for operating the shafts if desired.

The illustrated apparatus is adapted for 65 the carrying out of the invention relative to the production of a football cover. In practicing the invention by the use of the apparatus shown, the four similar leather parts 21 are utilized, and, when properly assembled, 70 they will constitute the cover of an ordinary oval-shaped football. These cover parts are suitably dampened and are then stretched and sewed together over said form, French seams 22 being preferably employed for such 75 purpose as indicated. On the side of the form where the shaft end 19 protrudes, the seam is not completed, along the central area two end portions 23 of seaming being formed leaving the usual gap or opening 24 for the insertion 80 of the usual rubber inflating ball. Lacing openings 25 are provided on opposite sides of the opening 24 for use after completion of the ball cover for the usual football lacing. After the sewing has been completed, while 85 the cover is still on the form, the seams may be flattened by pounding or rolling them against the form. Whether the pounding operation is carried out or not, after the cover has received its "set" on the form, the seam 90 portions 23 are ripped out to permit of removal of the cover from the form. The form is collapsed as much as possible by rotating shaft 13, and the cover is removed by being stripped from the form. Then the seam portions 23 are remade, preferably using the 95 same stitch holes which were left by ripping out the original seam portions 23. In this way, it is insured that the cover will be re-formed in exact conformity with the shape assumed originally over the form. If the same stitch holes are not employed for the resewing, care should be taken that the same is re-sewed substantially along the same lines of stitching so as to insure uniformity in the 100 product. Then the cover thus formed is reversed through the slit opening 24, and is 105 ready for use in the usual way. In this way, balls of absolutely uniform shape and contour may be produced, thus greatly adding to the 110

accuracy with which the same may be used. Where balls of different shapes and for different purposes are to be made, the form will of course conform to the desired exterior thereof, and the cover portions will also be varied in shape to correspond to facilitate the manufacture as desired.

This application is a division of my co-pending application, Serial No. 101,217, filed 10 April 10, 1926, in which the claims on the apparatus are presented.

What I claim is:

1. The method of making inflatable ball covers, comprising shaping and sewing cover parts together over a form and in the shape thereof; partially ripping said cover parts to permit removal from said form; removing the cover parts from the form; and then resewing said cover parts together substantially 15 where ripped.
2. The method of making inflatable ball covers, comprising shaping and sewing cover parts together over a form and in the shape thereof; partially ripping said cover parts to permit removal from said form; removing the cover parts from the form; and then resewing said cover parts together through the stitch 20 holes left by the ripping.

3. The method of making inflatable ball covers, comprising shaping and sewing cover parts 30 together over a form and in the shape thereof with the cover parts arranged inside out; flattening the seams of the cover parts against said form; partially ripping said cover parts to permit removal from said form; removing the cover parts from the form; then resewing the ripped seams using the same stitch holes; and then reversing said completed cover, an opening being left at one side of said cover through which the same is reversed and 35 through which an inflating member may be inserted therein.

4. In the art of constructing ball covers, forming cover parts into a cover over and conforming to the shape of the periphery of a 40 form, the cover parts being disposed thereon inside out; securing the edges of said cover parts about the form for snugly enclosing the form; detaching a sufficient extent of the edges to enable removal of the cover from the form; removing the cover therefrom; again attaching the detached edges and reversing the cover.

In testimony whereof I have signed my name to this specification.

JOHN T. RIDDELL.
